UNITED STATES PATENT OFFICE

ARTHUR E. BROWN, OF BURLINGTON, ONTARIO, CANADA

REFRIGERATOR UNIT

Application filed September 18, 1929. Serial No. 393,437.

The principal objects of this invention are, to overcome the difficulties of maintaining the freezing chamber of a cooling unit intact as against the disrupting influences of expansion and contraction due to change in temperature conditions, and further to provide means for retaining the low temperatures in a freezing chamber over an extended period.

The principal features of the invention consist in the novel use of a heat absorbing medium in comminuted form mixed with a binding cement as an insulator for a freezing chamber, and in the novel construction and arrangement of the cooling coil whereby the maximum surface contact between the cooling coil and the freezing chamber is obtained.

In the drawing, Figure 1 is a perspective view of a cooling section shown partly in section and partly broken away.

Figure 2 is an elevational sectional view of a unit shown on a slightly smaller scale.

In the construction herein shown the inner casing 1, which is preferably of rectangular form, has mounted thereon and surrounding it from end to end a coil 2 of copper piping, one end of which is directly connected to the expansion valve of the refrigerating system, which is not herein shown.

The convolutions of the coil 2 are formed of a plurality of straight sections 3 arranged in progressively right angular relation and connected by the bent loops 4 which extend around the corners of the rectangular casing in such a manner that there are no angles or sharp bends and yet a very considerable length of tubing is arranged in close parallel arrangement with the inner wall of the freezing chamber.

A rectangular casing 5 spaced from the inner casing 1 and also spaced from the convolutions of the coil 2 forms an enclosed chamber around said inner coil and inner chamber and this closed chamber is filled with a cement 6 composed of iron, copper, brass, aluminum or other metal fillings intimately mixed with a suitable cementitious binding material such as litharge.

The terminal end 7 of the coil 2 extends

out through the side wall of the casing 5 and forms the outer cooling coil 8.

The convolutions of the coil 8 are supported on the tubular members 9, preferably in heat interchange contact, which members 9 are secured to the longitudinal corners of the outer casing 5 and heat conducting vanes 10 of suitable dimensions are secured to the outer coils.

The refrigerator element above described is arranged in any suitable form of refrigerator cabinet and the coil 8, external to the freezing chamber, absorbs heat directly from the surrounding atmosphere and from the vanes 10, but the temperature of the refrigerating gases flowing through this coil is not sufficiently low to create frost of any appreciable thickness on the surfaces.

The inner coil which receives the refrigerating gases when first expanded carries the refrigerator element at a temperature below freezing and this temperature is utilized to absorb the heat in the enclosed space within the inner casing or freezing chamber where goods requiring to be reduced to a temperature below freezing are placed.

The looped corners of the coil allow the expansion and contraction thereof without fracture and the filling of the space surrounding the inner casing with the comminuted metallic substance presents a heat absorbing agent of such slow action as to form an effect ve insulation for the interior chamber, but which will conduct a certain amount of external temperatures to the cooler inner coils 2.

This cement loaded with the comminuted metal particles takes the place of the brine chamber that has been in common use and eliminates the difficulties of expansion and contraction which eventually cause leakage.

An element such as described is very effective in use. It is cheap to construct and will not get out of order.

What I claim as my invention is:—

1. A refrigerating unit, comprising a casing, a coil of tubing encircling said casing, a coil of tubing spaced from and encircling the former coil, said first-mentioned coil being embedded in a solid filler of predetermined

heat exchange value disposed mainly on the outward side thereof whereby a greater heat exchange will be effected between the embedded coil and the interior of the casing than between the embedded coil and the exterior of the casing.

2. A refrigerating unit, comprising an inner casing, a coil of pipe encircling said inner casing having a plurality of straight portions arranged parallel with the side of said casing, an outer coil forming a continuation of the inner coil, and a solidified filling containing comminuted metal particles interposed between said coils and forming a heat exchange medium of predetermined value.

3. A refrigerator unit, comprising an inner casing, a coil of pipe encircling said inner casing and having straight portions in close association with the side wall of the said casing, an outer casing spaced from said inner casing and enclosing said coils, a filler of comminuted metallic substance mixed with a cementitious binding arranged between said casings, and an outer coil encircling the outer casing and connected with the inner coil.

25 4. A refrigerator unit as claimed in claim 3 in which said cementitious binding comprises litharge.

30 5. A refrigerator unit, comprising an inner casing, a coil of pipe encircling said inner casing having straight portions lying in close relation to the walls thereof, an outer casing spaced from said inner casing and enclosing said coils, a filling of comminuted metal mixed with a plastic cement encasing said coil and inner casing between said inner and outer casings, and an outer coil encircling the outer casing.

6. A refrigerator unit, comprising an inner casing, a coil encircling the inner casing, an outer casing enclosing said coil and spaced from the inner casing, a filler of predetermined heat exchanging properties arranged between the casings, tubular members arranged longitudinally of the corners of the outer casing, a coil forming a continuation of the inner coil wound around the outer casing and in contact with the longitudinal tubular members, and heat conducting vanes secured to the outer coil outside of the outer casing.

ARTHUR E. BROWN.
